PILOT FOR VAPORIZING BURNERS

Filed Aug. 29, 1947

UNITED STATES PATENT OFFICE

2,579,293

PILOT FOR VAPORIZING BURNERS

James L. Breese, Santa Fe, N. Mex., assignor to
 Breese Burners, Inc., Santa Fe, N. Mex., a corporation of Delaware

Application August 29, 1947, Serial No. 771,203

2 Claims. (Cl. 158—91)

1

My invention relates to an improvement in liquid fuel burners and has for one purpose to provide an improved mechanism for maintaining a minimum or low turned-down fire.

Another purpose is to provide an improved pilot piece or housing for liquid fuel burners.

Another purpose is to provide an improved method of low-fire or pilot combustion.

Another purpose is to provide improved means for burning and for hydroxylating liquid fuel in a pot type burner when the burner is supplied with liquid fuel at a minimum or pilot rate.

Another purpose is to provide an improved securing means for removably securing a pilot housing in position in a burner.

Another purpose is to provide a pilot structure adapted to operate, and to maintain a pilot flame, at a rate or rates of fuel flow substantially less than the operating rates of pilot structures heretofore available.

Other purposes will appear from time to time in the course of the specification and claims.

I illustrate the invention more or less diagrammatically in the accompanying drawings wherein:

Fig. 1 is a vertical section;

Fig. 2 is an enlarged vertical section;

Fig. 3 is a horizontal section, on the line 3—3 of Fig. 2; and

Fig. 4 is a section taken on the line 4—4 of Fig. 2.

Referring to the drawings, 1 generally indicates an outer housing having a plurality of feet 2 between which are air inflow spaces 3. The housing is partly closed by a horizontal partition 4 centrally apertured as at 5. 6 is an angle ring which receives the upper outwardly extending flange 8 of a burner pot 7. 9 indicates an upper portion of the housing 1, which serves as a combustion chamber, or a heat radiating member. Any suitable draft means, not herein shown, may be provided for disposing of the heated gases and by-products of combustion. One end of the pot is partially closed by a centrally apertured flame ring 10. The pot is shown as having a slightly concave bottom or closed end 11 and a generally cylindrical side wall 12 provided with a plurality of primary air inlet apertures 13, circumferentially spaced about the wall 12 and located at various distances above the pot bottom. A liquid fuel is supplied to the pot along the pipe 16, the rate of flow being controlled by any suitable control means generally indicated as 17. I illustrate, for example, a known type of float valve assembly with a manual control knob 18 for con-

2

trolling the flow of fuel along the pipe 16. However, it will be understood that any suitable control means, manual or automatic, may be provided for varying the rate of flow of liquid fuel along the pipe 16 or for maintaining a uniform rate of flow, when a uniform rate is desired.

It will be understood that in pot type burners of the present type, a liquid hydrocarbon is vaporized by the heat of combustion taking place in or above the pot. The liquid hydrocarbon is admitted to the interior of the pot and is initially partially vaporized by the heat of combustion taking place in the pot. As the liquid hydrocarbon is vaporized in the pot it rises and is surrounded by a film of secondary air. The radiant heat from the ensuing complete combustion supplies the remainder of the additional heat necessary to vaporize all of the liquid hydrocarbon. There is a differentiation in action between the so-called primary air and the so-called secondary air admitted to the interior of the pot. With reference to the present structure, the air entering through primary apertures 13, has a different action than the air entering through the secondary apertures 25. All of the oxygen in the air entering through the primary apertures 13 is fully consumed in the process of hydroxylation. I provide any suitable secondary air inlet apertures such as are shown at 25. It will be understood that secondary air is admitted through the apertures 25, to form with primary mixture a final mixture which is burned at or beyond or above the top or open end of the pot.

I locate a pilot member or piece which rests upon the bottom 11 of the pot and which should snugly abut against a lower part of the pot side wall. It is shown as surrounding the space to which liquid fuel is delivered by the duct or pipe 16. The pilot piece which I indicate generally as 30 is shown as having two inwardly converging side walls 31 with top flanges 32. The lower edges of the side walls 31 snugly engage the upper surface of the pot bottom 11. The side walls have flanges 33 at their outer ends which engage the inner surface of the pot side wall. The pilot side walls 31 are connected by an inner end wall 34 which has an outlet 35 connecting the interior of the pilot piece with the interior of the rest of the pot. In the structure herein shown I illustrate a sheet metal pilot piece. It will be understood that it may be cast or otherwise suitably formed. In the particular structure herein illustrated I show an intermediate plate 36 the outer edges of which overlie and conform to the flange 32. Positioned above the plate 36 is an upwardly

domed or offset cover plate 37 which, with the plate 36, forms a plenum chamber. The function of this chamber is to supply air to the liquid fuel vaporized within the pilot piece 30. I provide an air inlet duct 38 the outer end of which extends as at 39 through an appropriately formed aperture in the pot side wall 12. 40 is a nut adjustable on the screw threaded end 39 of the duct 38. 41 is a bracket on the duct 38, located within the pot. It carries a suitable thrust member, such as the screw 42, which may be employed adjustably to direct a controlled or predetermined thrust against the inner face of the pot side wall 12. By using the structure above described, and by properly adjusting the nut 40 and the screw 42, the pilot piece 30 may be held firmly in the position in which it is shown in Figures 1 and 2, with a substantial elimination of leakage about the edges of the pilot side walls 31.

Air from the space between the housing 1 and the pot 12, flows through the duct 38 and into the plenum chamber 37. The air is admitted to the space about the pot through the aperture 5. If desired a booster motor and fan may be positioned in the aperture, or other means may be employed for maintaining a suitable air pressure about the pot.

Air from the plenum chamber flows downwardly into the space within the pilot piece 30, through a plurality of primary air inlets 45. These are shown as arranged in a series of rows, but their particular size and arrangement may be varied. They provide primary air for the initial hydroxylation of the liquid hydrocarbon fuel which flows through the pipe 16 into the interior of the pilot piece 30. The final or secondary air supply is shown as provided by a single row of secondary air inlets 46 positioned adjacent the outlet 35. It will be noted that I show secondary air inlets which are both larger and more closely spaced than the primary air inlets and which direct a substantial concentration of secondary air adjacent the point of escape of the mixture from the interior of the pilot housing 30. Thus the liquid fuel flows across the bottom of the pilot housing, in a very thin stream, and, at minimum rates of combustion, almost drop by drop. I may find it advantageous to delay the flow of the liquid fuel by providing a somewhat flattened area, shown at 50 in the bottom of the pot and located just beneath and inwardly of the point of delivery of the liquid fuel from the pipe 16.

It will be understood that whereas I have described and shown a practical and operative device, nevertheless many changes may be made in size, shape, number and disposition of parts without departing from the spirit of my invention. I therefore wish my description and drawings to be taken as in a broad sense illustrative or diagrammatic, rather than as limiting me to the specific showing herein. For example I may employ or omit the flattened pot bottom surface 50. I may substantially change the size and arrangement and shape of the apertures 45 and 46. And I may use sheet metal or other suitable metal for forming the pilot piece herein shown.

The use and operation of the invention are as follows:

I provide a pilot piece which receives its liquid fuel from the normal fuel inlet of a pot type burner. I avoid the use of a pool or dam or depression by employing the bottom of the pot it-

self as a trough or flowing surface over which the fuel flows. Under some circumstances it is advantageous to move the oil by gravity as rapidly as possible from the inlet pipe to the center of the burner. In that event I omit the flattened position 50. Under other circumstances it may be desirable somewhat to slow down the flow of the fuel. In that event I may employ the flattened surface 50. I find it advantageous to prevent any damming or pool formation which would cause a clogging with asphalt or hard carbon. I find that in the ordinary burner bottom, where the slant of the pot is less than one-eighth inch to the foot, the oil spread is unsatisfactory. I therefore generally use the small trough surface or depression 50 immediately along the center of the plate 36. By using it the oil is rapidly moved down through the center in a thin stream. By the time it reaches the secondary air holes 46, it has been completely vaporized and hydroxylated. And under no circumstances do I permit the formation of a pool of liquid fuel.

In hydroxylating the pilot fuel I find it important to delay the formation of a defined flame in the pilot zone, which could result in coking the liquid hydrocarbon, with a resultant deposit of carbon and ultimate stoppage of the oil flow. I so arrange and proportion the apertures 45 as to provide air in insufficient amounts to produce a flame. The flame does not begin until the fuel or mixture has reached the zone of admission of secondary air, at which time all liquid hydrocarbon on pilot fire has been completely vaporized and hydroxylated.

To summarize the action of my pilot structure, I move a thin layer of liquid fuel at a substantial rate of flow, through a zone in which it receives primary air in a relatively scant quantity, insufficient for flame formation. The fuel is vaporized in response to combustion at, near, or beyond the inner end of the pilot piece 30. Flame does not begin until the primary mixture receives the secondary air. I thus employ, in effect, a gravitational feed or flow of fuel, along the relatively narrow trough 50, by which the liquid moves with substantial rapidity until vaporized. One advantage of the structure is that it can be supplied with liquid fuel with a relatively low head of liquid.

I claim:

1. In a pilot housing for pot type liquid fuel burners, inwardly converging side walls having end portions formed and adapted to engage the inner surface of a burner pot side wall, bottom edge portions adapted to engage and conform to the burner bottom, and an inner end wall uniting the inner ends of said side walls, and having a flame outlet, a plenum chamber overlying and closing the space between said pilot side walls and an air inlet duct extending from said plenum chamber upwardly and adapted to extend outwardly through the side wall of the pot, and members on said air inlet duct adapted to thrust said pilot housing downwardly against the pot bottom and outwardly against the pot side wall, said members including a pot wall engaging abutment adapted to be placed exterior to the pot and an offset abutment on said air inlet duct, adapted to engage the inner face of the pot side wall.

2. The structure of claim 1 characterized in that the pot wall engaging abutment and the offset abutment on the air inlet duct are mounted for adjustment along the air inlet duct whereby, when they are tightened, the pilot housing is

5

thrust downwardly and outwardly against the pot wall.
